(57) **CLAIM**

The ornamental design for a microscope table, as shown and described.

DESCRIPTION

FIG. 1 is a top, right perspective view of a microscope table according to our design;

FIG. 2 is a bottom, right perspective view thereof;

FIG. 3 is a top, left perspective view thereof;

FIG. 4 is a bottom, left perspective view thereof;

FIG. 5 is a top view thereof;

FIG. 6 is a bottom view thereof;

FIG. 7 is a front view thereof;

FIG. 8 is a rear view thereof;

FIG. 9 is a right view thereof; and,

FIG. 10 is a left view thereof.

The broken lines form no part of the claimed design.
